UNITED STATES PATENT OFFICE.

JULIAN O. ELLINGER, OF NEW YORK, N. Y.

REINFORCEMENT FOR CONCRETE CONSTRUCTION.

1,087,439.

Specification of Letters Patent.

Patented Feb. 17, 1914.

Application filed June 23, 1909. Serial No. 503,773.

To all whom it may concern:

Be it known that I, JULIAN O. ELLINGER, a citizen of the United States, and a resident of the city, county, and State of New York, have invented certain new and useful Improvements in Reinforcements for Concrete Construction, of which the following is a specification.

This invention relates to improvements in reinforcements for concrete beams, girders and the like, and it relates more particularly to that class of reinforcements, wherein the tension members and the shear members are connected and form an open frame to be embedded in the concrete.

One of the objects of the invention is to provide a novel, and at the same time, simple construction that can be produced at small cost, and has a high degree of efficiency.

Still another object is to provide a reinforcing structure which is capable of great latitude in form, so that it may be accommodated to the various conditions encountered.

Several embodiments of the invention are disclosed in the accompanying drawings, but it will be evident from an inspection of the claims hereto appended that the invention is not necessarily limited to these forms.

Referring to the drawings, in which the same reference character indicates the same part in the several views: Figure 1 is a perspective view, showing two of the reinforcements in assembled and cross relation. Figs. 2, 3, 4 and 5 are side elevations, showing different forms of bracing. Fig. 6 is a detail view showing still another modification, in which the shear elements are extended above the upper longitudinal or tension bar. Fig. 7 is a detail side elevation illustrating a modified arrangement of the shear elements. Fig. 8 is a cross sectional view. Fig. 9 is a cross sectional view showing sets of shear elements arranged on opposite sides of the longitudinal bars.

Referring first to the embodiment disclosed in Fig. 1, it will be observed that a plurality of sets of lower longitudinal bars or tension members 10 are employed, which are preferably continuous from end to end of the structure, these members being located

in spaced relation and any number being employed, as desired. Arranged above each lower longitudinal bar is an upper bar, preferably made of sections 11 that are disposed preferably only over the end portions of the bars 10, and extend beyond said ends. 60 The upper and lower tension members or bars are connected by vertical bars or shear elements 12, while the different sets of bars are preferably connected by tie elements 13, said tie elements consisting of plates having 65 openings 14, through which the longitudinal bars are passed. If desired, for the purpose of further strength, auxiliary longitudinal bars 15 may be employed that connect the innermost shear elements 12. It 70 will be evident that a light but very rigid reinforcing frame is thus produced, and as each member constitutes a complete unit, in itself, it may be associated with as many more members, as is found desirable or 75 necessary, depending on the conditions encountered.

In Fig. 1, two crossed reinforcements are disclosed, one consisting of three units, the other of two. The latter extends through 80 and over the former, and certain of the upper sections, as 11^a thereof, have their inner ends overlapped, as disclosed at 11^b, and connected by tie plates 11^c. As shown, the overlapping is accomplished by having 85 the end of one bar placed over the end of the other bar. This overlapping, however, may be accomplished by having the ends of the bars on the same level, so that they lie side by side. 90

In order to indicate how the structure may be modified, attention is invited to Figs. 2 to 5 inclusive. In Fig. 2, a lower longitudinal or tension member 16 is employed, and above it is arranged an upper 95 longitudinal or tension member 17 that is continuous and longer than the lower member. Upright shear bars or elements 18 connect these members, and braces 19 are also preferably employed, that extend diagonally from the upper to the lower member, across the shear elements. The said shear elements are arranged only at the end portions of the longitudinal bars, and the intermediate portions are connected by convergently disposed diagonal braces 20. Sub-

stantially the same structure is disclosed in Fig. 3, and the same reference numerals have therefore been employed for corresponding parts. However, the intermediate 5 bracing is slightly different, inasmuch as crossed stays 21 are provided that bridge the space between the upper and lower tension bars, and the innermost shear elements.

In Fig. 4, still another arrangement of 10 intermediate bracing is disclosed. An auxiliary longitudinal bar 22 connects the innermost shear elements 18, and convergently disposed diagonal braces 23 extend from the upper bar to the central portion of the lower 15 bar. In Fig. 5, crossed braces 24 are employed in connection with an auxiliary longitudinal bar 25.

In order to secure a more perfect bond 20 between a floor slab and a beam or girder, the shear elements, as disclosed at 18^a in Fig. 6, may be extended above the upper longitudinal bar so that they will be embedded as high as possible in the floor slab.

In all the above forms, it will be noted 25 that the distance between the shear chords or elements decreases as the distance of said elements from the ends of the longitudinal bars increases, thus insuring proper strength at the points distant from the ends of the 30 frame or reinforcing member. Instead of decreasing this distance by employing shear elements of the same width, different distances apart, the said shear elements may be successively increased in width, as shown 35 at 26 in Fig. 7. It will be obvious that this arrangement secures the same desirable results. Attention is also invited to Figs. 8 and 9, wherein it will be evident that the 40 shear elements may be located on one side only of the upper and lower bars or tension members, or may be placed on both sides, and it will also be noted by reference to these 45 figures that the upper longitudinal bars are preferably made of less cross sectional area than the lower.

From the foregoing it is thought that the construction, operation and many advantages of the herein described invention will be apparent to those skilled in the art without further description, and it will be understood that various changes in the size, shape, proportion and minor details of construction may be resorted to without departing 50 from the spirit or sacrificing any of the advantages of the invention.

Having now described my invention, what I claim as new and desire to secure by Letters Patent is:

1. In a reinforcement for concrete construction composed of a plurality of standardized unitary reinforcing frames, each frame including a lower longitudinal bar and an upper longitudinal bar, placed over the lower bar, the said upper bar being so

arranged that when assembling one frame 65 with the other with the ends in reversed order the meeting end of one upper bar will overlap the adjacent end of the other bar.

2. In a reinforcement for concrete construction composed of a plurality of standardized unitary reinforcing frames, each frame comprising a lower longitudinal bar and two short bars placed over the ends of each of the lower bars, the outer ends of each of the upper bars extending beyond 70 each end of the lower bar, the upper bar of one end being in a different plane from that in which the opposite upper bar lies, whereby in assembling one frame with another the ends are reversed so that the upper bar on 75 one frame will overlap the upper bar of another.

3. In a reinforcement for concrete construction composed of a plurality of standardized unitary reinforcing frames, each 80 frame comprising a lower longitudinal member, upper members composed of separate sections substantially parallel to the lower member, transverse members connecting the lower member and each of the upper 85 members, the outer end of each upper member extending beyond the corresponding end of the lower member and in different planes, whereby in assembling one frame with another with the ends reversed the upper bar 90 of one frame will overlap the upper bar of another frame.

4. A reinforcement for concrete construction, comprising upper and lower longitudinal members, the upper member composed 100 of separate sections substantially parallel to the lower member, the said upper sections being in different horizontal planes, transverse tie or shear members connecting the lower member and the said sections of 105 the upper member, whereby in assembling one construction with another end to end the upper sections will overlap.

5. A reinforcement for concrete construction, comprising upper and lower longitudinal members, the upper member composed 110 of separate sections located over the ends and substantially parallel to the lower member, with the outer ends thereof projecting beyond the ends of the lower member, transverse tie or shear members connecting said sections to the said lower member, said upper sections being substantially 115 parallel to the lower member, but in different planes with each other, whereby in assembling one construction with another end to end the end sections will overlap.

6. A reinforcing frame for concrete construction, comprising upper and lower longitudinal members, the upper members having 125 their outer ends coextensive and projecting beyond the ends of the lower members, transverse shear members connecting said

upper members to the said lower members, said upper members being substantially parallel to the lower members, the upper members at one end of the frame being in 5 planes different from those in which the upper members at the opposite end of the frames are arranged, whereby in assembling one frame with another, with the lower horizontal members contacting end to end, the end portions of the upper members will 10 overlap.

In witness whereof I have hereunto set my hand at the city, county and State of New York, this 15th day of June, 1909.

JULIAN O. ELLINGER.

In presence of—

ISABEL R. RICHARDS,
JOHN J. RANAGAN.
